STRINGING DEVICE

John F. Carlile, Paterson, N. J., assignor to United Fruit Company, Boston, Mass., a corporation of New Jersey

Application April 9, 1949, Serial No. 86,418

5 Claims. (Cl. 289—1)

1

This invention relates to a device for looping strand materials around extended objects, for example, for stringing banana stalks or the like.

An object of this invention is to provide a device by means of which objects can be easily and quickly strung, and, in the case of banana stringing, without damage of the type which is often caused by stringing wholly by hand.

Other objects and advantages will appear from the following description, taken in conjunction with the accompanying drawings in which:

Fig. 1 is a plan view of the device;

Fig. 2 is a side view of the device;

Fig. 3 is a view of the device encircling a banana stalk;

Fig. 4 is a partial view of the device being withdrawn from the stalk in the direction of the arrow, and

Fig. 5 is a perspective view of a modified form.

Devices of this invention comprise a handle having extending therefrom a flexible, resilient strip which is held against separation from the handle. An element is mounted on the handle for longitudinal movement relative thereto and a flexible strand extends between the element and the free extremity of the resilient strip. The strand and strip extend in relatively spaced relation so that when the element is moved inwardly of the handle, the strand will flex the strip and curl inwardly towards the handle. Additionally, the device is provided with retaining means extending between the strip and the strand for maintaining the strand against any substantial separation away from the strip during the curling motion of the extremity of the strip so that a relatively large loop is presented when the element is moved inwardly of the handle.

The drawings show two forms of retaining means and strip construction. In the form of Figs. 1 to 4 inclusive, handle 1 has thumb loop 2. Slidably mounted on the handle is element 3. Affixed to the under side of the handle and extending beyond its end is a flexible strip comprising a sheath 4, as of tubular fabric. Affixed along this sheath 4 beyond the end of the handle is a series of truncated, wedge-shaped blocks 5 as of wood, terminating with an end piece 6. The end piece 6 is provided with a hook 7. The sheath 4 contains a resilient metal strip 8 which is anchored with the sheath 4 by screw 9 to end piece 6. Strand 10 is anchored at its inner end to element 3 and passes through a portion of the handle as shown at 11 and through holes 12 in the blocks 5 with its outer end anchored on the end piece 6.

2

Because the strand 10 extends in spaced relation to the resilient flexible composite 4 and 8, when the element 3 is moved inwardly of the handle 1, the extremity and the hook 7 will curl as shown in Fig. 3, the blocks 5 acting as retaining means to prevent the strand 10 from pulling away from the resilient composite. During this action, the strip 8 is free to move in the sheath 4 outwardly along the handle 1.

In operation, a closed loop of rope is placed over the operator's forearm or wrist; the thumb of the operator is inserted in the loop 2; and the index and middle fingers are placed, one on either side of the handle 1, over and around the block 3.

15 The device is positioned beside a banana stalk in a substantially straight condition with the blocks 5 nearest the handle 1 adjacent to said stalk. By rearward pressure of the index and middle fingers upon the element 3, the latter is drawn backwards causing tension in the strand 10, thereby forcing the portion of the device containing the blocks 5 and end piece 6 together with the hook 7 to curl back towards the operator's hand around the stalk, Fig. 3. One end of 20 the rope loop is then placed upon the hook. The pressure upon the element 3 is then released relieving the tension in the strand, the device is straightened out by means of the inherent resiliency of the strip 8, and is withdrawn away from the stalk to form the loop of rope into a knot, known as a bale sling, around the stalk.

In the form shown in Fig. 5 the retaining means, instead of comprising a series of blocks 35 5 as in the form of Figs. 1-4, consists of a coil spring 14 which is anchored at one end to the metal handle 1a and loops around a flexible resilient strip 8a and the strand 10a. In this form, the end piece and hook may be an integral portion of the flexible resilient strip 8a which may be of spring steel having a resilient slightly curved shape as shown. In this form the strip 8a may be rigidly affixed to the handle as by rivets 15, whereas the coil spring 14 and strand 10a may be affixed to the outer extremity of the strip 8a by passing through an aperture 16 in an offset portion of strip 8a forming the end pieces and bent into a secure position. As shown, the element 3a is formed of tubular metal slotted to receive the handle 1a. The operation of the device is the same as that of Figs. 1-4.

It will be readily understood that other suitable materials may be employed to comprise the various elements of the device, that said elements may be secured to one another by other suitable means, and that said elements may be of other

suitable sizes and shapes, without departing from the spirit of this invention as set forth in the appended claims.

Having described my invention, I claim:

1. A device of the character described comprising a handle, an element mounted on said handle for longitudinal movement relative thereto, a flexible resilient strip extending beyond one end of said handle and held against separation therefrom, a flexible strand anchored at one of its ends to said element and at its other end to said strip, at a point remote from said handle, said strand extending in laterally spaced relation to said strip, and retaining means extending between said strip and said strand for maintaining said strand and strip against any substantial relative separation long substantially the entire length of said strand as said element is moved longitudinally relative to said handle in a direction away from said remote point to flex said strip, whereby the extremity of said strip curls inwardly towards said handle to permit an article, such as a rope, detachably secured to said extremity after it has been curled around an object by such element movement, to be looped around said article as said element is released to uncurl said strip with simultaneous withdrawal of the device away from said object.

2. A device of the character described comprising a handle, an element mounted on said handle for longitudinal movement relative thereto, a flexible resilient strip extending beyond one end of said handle and held against separation therefrom, a series of wedge-shaped blocks secured in a row along one side of the extending portion of said strip, and a flexible strand anchored at one of its ends to said element and anchored at its other end to said strip at a point remote from said handle, for curling said strip inwardly towards said handle as said element is moved longitudinally relative to said handle, in a direction away from said remote point, and a rope retaining means mounted adjacent the outer end of said strip for connecting a piece of rope thereto for passage around an article extending through the loop formed by the strip in its curled position.

3. A stringing device comprising a handle, a flexible sheath secured to said handle and extending beyond one end thereof, a series of wedge-shaped blocks secured in a row along one side of

the extending portion of said sheath, a resilient member carried in said sheath for relative longitudinal sliding movement therein but anchored at its outer end to said sheath, an element slidably mounted on said handle and a flexible strand anchored at one of its ends to said element and extending through said series of blocks, and anchored at its other end adjacent the outer end of said sheath, for flexing said sheath into a curled position upon movement of said slideable element inwardly of said handle, and a rope retaining means mounted adjacent the outer end of said sheath for connecting a piece of rope thereto for passage around an article extending through the loop formed by the sheath in its curled position.

4. A device of the character described comprising a handle, an element mounted on said handle for longitudinal movement relative thereto, a flexible resilient strip extending beyond one end of said handle and held against separation therefrom, a flexible strand anchored at its inner end to said element and at its outer end to said strip at a point remote from said handle, said strand extending in laterally spaced relation to said strip along a substantial portion of its length, and retaining means extending between said strip and said strand for maintaining said strip and strand against any substantial relative separation along substantially the entire length of said strand as said element is moved longitudinally relative to said handle in a direction away from said remote point to flex said strip, said retaining means comprising a helically wound wire anchored at one end to said handle and at its other end to said strip adjacent its free extremity whereby the extremity of said strip curls inwardly towards said handle to permit an article, such as rope, detachably secured to said extremity after it has been curled around an object by such element movement, to be looped around said article as said element is released to uncurl said strip with simultaneous withdrawal of the device away from said object.

5. A device of the character claimed in claim 1 wherein the flexible strip is provided at its extremity with an offset portion and a hook, both integral with said strip.
